[57] CLAIM

The ornamental design for a vehicle panel guard, substantially as shown and described.

DESCRIPTION

FIG. 1 is a side elevational view of a vehicle panel guard showing my new design installed along the forward edge of the rear wheel well of a truck type vehicle which has been fragmentarily shown in broken lines for illustrative purposes only;

FIG. 2 is an enlarged rear elevational view thereof;

FIG. 3 is an enlarged side elevational view thereof;

FIG. 4 is an enlarged front elevational view thereof;

FIG. 5 is an enlarged top plan view thereof;

FIG. 6 is an enlarged bottom plan view thereof;

FIG. 7 is an enlarged side elevational view thereof opposite to that shown in FIG. 3; and

FIG. 8 is an enlarged perspective view thereof.
